(57) **CLAIM**

The ornamental design for a needle holder, as shown and described.

DESCRIPTION

FIG. 1 is a perspective view of a needle holder according to our design;

FIG. 2 is a front view of the needle holder, a rear view being symmetrical to the front view;

FIG. 3 is a top plan view of the needle holder;

FIG. 4 is a bottom view of the needle holder;

FIG. 5 is a left side view of the needle holder;

FIG. 6 is a right side view of the needle holder; and,

FIG. 7 is a sectional view of the needle holder taken along lines 7-7 in FIG. 6 for showing needle-holding holes.
